Filed Aug. 2, 1960, Ser. No. 46,972

13 Claims. (Cl. 100—93)

This application relates to liquid expressing presses of the continuous type in which bulk material such as sucrose bearing fibrous materials (i.e., sugar cane, sugar beets, etc.) as well as other meals, nuts, and the like can be subjected to high relatively continuous pressures, for example in the order of five to six thousand p.s.i. or higher, with the sucrose, juice, oils, or the like being expressed therefrom and collected apart from the relatively dry expressed bulk which is discharged from the press.

A preferred type of screw press construction for this purpose involves a cage including screen bars in the walls thereof which define minute openings through which the liquid may pass while containing the solids within the cage under the relatively high pressures. A rotary driven shaft extends through the cage and on this shaft are mounted alternately feeding or pressure worms and pressure collars, each of which may or may not be tapered radially outward in a direction from the inlet toward the discharge end of the cage, depending upon the particular action desired in that segment of the cage in which the particular flight and/or collar is located. In the area of the collars, projecting from the cage wall toward the surfaces of the collar, there is at least one breaker bar or lug which resists rotation of the compacted material in this area and thus causes the material to pass axially through the press, in response to the pressure exerted thereon by the preceding worm flight. Generally speaking, the cross sectional area of the passage through the press, between the cage walls and the worms and collars around the shaft, decreases from the inlet to the discharge end of the cage, and the pressures exerted will increase, into the neighborhood of, for example 10,000 p.s.i. in the portions of the passage of considerably lesser cross-sectional area.

In these areas the material becomes much drier and harder, since considerable liquid has been expressed, and sufficient horsepower must be applied to the shaft carrying the worms and collars to overcome the friction between the hard material and the rotating shaft parts. As the pressure in the cage increases, the frictional load increases proportionately. The breaker bars located adjacent to the collars prevent the rotation of the material as it passes over the collars and this insures a frictional load between the rotating collar and the non-rotating material. This frictional load is responsive for a great portion of the power required to turn the shaft.

Accordingly, the primary object of this invention is to provide an improved liquid expressing press construction in which the frictional force exerted upon the collars by the material passing thereover is considerably reduced by eliminating the frictional component due to the rotation of the collar with respect to the material.

Another object of this invention is to provide such a press construction wherein the spacer collars between pressure worms are essentially free to rotate upon the shaft, and wherein bearing surfaces are provided between the shaft and such collars, including if desired anti-friction bearings.

Another object of this invention is to provide a stationary discharge collar about the shaft at the discharge end of the press cage, and preferably mounted from the cage and adjustable with respect thereto along the axis of the

2

shaft such as to control the discharge areas at the end of the press through which the material is expelled.

An additional object of the invention is to provide such a discharge collar with drainage connections providing for removal of expressed liquid through the stationary discharge collar as well as through the openings in the walls of the press cage.

A further object of the invention is to provide in the mountings of such stationary discharge collar a connection whereby the collar may be withdrawn well to the outside of the press to release pressure on the material in the event that it is necessary to shut down the press for some period of time and then to start again.

Another object of this invention is to provide a novel arrangement for flushing foots and the like from the discharge collars.

A further object of the invention is to provide novel cooling arrangements for a high pressure expressing press.

An additional object of the invention is to provide a novel discharge collar arrangement through which liquids can be flowed in a direction to provide addition or impregnation of liquid into the relatively dry material, within the press, from which liquid has been expressed.

Another object of the invention is to provide apparatus for burning loose plugs of dry material which may form adjacent the press discharge, particularly during starting of the press.

Other objects and advantages of the invention will be apparent from the following description, the accompanying drawings and the appended claims.

In the drawings:

FIG. 1 is a somewhat diagrammatic view in the form of a longitudinal section, with some parts shown in elevation, through essential parts of an expressing press in accordance with the invention;

FIG. 2 is an enlarged sectional view of a portion of the press, illustrating the mounting of the collars and discharge sleeve within the press;

FIG. 3 is a detail sectional view taken on line 3—3 of FIG. 2;

FIG. 4 is a sectional view taken on line 4—4 of FIG. 2;

FIGS. 5 and 6 are fragmentary views illustrating op-

tional features of the invention;

FIG. 7 is a section taken on line 7—7— of FIG. 5;

FIG. 8 is a section taken on line 8—8 of FIG. 6;

FIG. 9 is a view of a modified construction generally similar to FIG. 6; and

FIGS. 10 and 11 are, respectively, a longitudinal sec-

tion and a cross-section view showing another modifi-

cation.

Referring to the drawings, and particularly to FIGS. 1—4, the liquid expressing press includes a main cage 10 which is made up of complementary halves forming a generally cylindrical elongated chamber 12. For exam-

ple, the cage may include semi-cylindrical halves 13 and 14, as shown particularly in FIG. 4, which are suitably bolted together when the press is in an operative condition. The drainage spaces are provided by a series of screen bars 15 which are suitably supported in the cage

sections and separated by spacers (not shown) which define minute spaces between the bars at the inner surfaces thereof through which expressed liquid may pass to the exterior of the cage, where it is collected in a pan or the like beneath the cage in well known manner.

A main shaft 20 extends coaxially through the press cage and is rotated by a suitable drive mechanism indicated schematically at 21. At the inlet end of the cage there is mounted a housing 22 including an inlet opening 23 through which liquid bearing materials are supplied, and also including a feed chamber 24 of generally cylindrical shape which is aligned with and opens into the inlet end of the main cage. Surrounding the shaft 20 in this

area is a feed worm 25 which is rotatable independently thereof by a separate, usually faster rotating, connection with the drive, including at least one driving lug or dog 26.

Within the body of the cage, mounted on shaft 20, are alternately arranged collars 30 and feed or pressure worm bodies 32 each having a worm flight 33 extending into close proximity with the interior wall of the cage. Adjacent the discharge end a discharge collar 35 is mounted through a supporting bracket 36 which is fastened to the cage structure and includes adjusting bolts 37 and spacers 38 providing a means for adjusting the position of the tapered discharge collar or sleeve along the length of the shaft to vary the cross-sectional area of the discharge opening which is defined by the collar and the surrounding ring 39 mounted also on the cage body. Relative movement between collar 35 and the preceding worm body is accommodated by an interfitting telescoping arrangement, indicated by the general reference numeral 40, or by any other suitable construction.

As shown particularly in FIG. 2, each of the collars 30 and pressure worm bodies is a separate element. These collars may be of constant diameter as shown, or some of them have a tapered outer configuration, increasing in area toward the discharge end of the press to decrease accordingly the cross-sectional area through which the material must pass. The worm bodies 32 are connected for driven movement with shaft 20 by means of keys 42, there being one key for each worm as shown. Surrounding the shaft within each collar 30 there is a cylindrical spacer 43 which abuts the worm bodies to maintain proper spacing therebetween for free relative rotation between the worm bodies and collars 30. Also, on the interior of each collar there is a bearing, which may be formed on the interior of the collar, or be a separate element, for example in the form of a separate sleeve 44. Thus, each of the collars 30 is capable of independent rotation upon the shaft 20, but is essentially confined against axial movement thereon by reason of its mounting between worm bodies 32. The last worm body is maintained in position by a threaded connection at 45 to the end of shaft 20, and this holds the entire assemblage fixed axially upon the shaft. Preferably, as shown in FIG. 2, the downstream (toward the discharge) ends of the collars are engaged with hardened thrust washers 47 which abut the following worm body 32 and provide a bearing surface accommodating relative movement between the adjacent worm and collar.

Accordingly, when shaft 20 is rotated by the drive, the worm bodies 32 will rotate therewith, and the worm flights 33 will force the material toward the following collars and succeeding worms. As previously explained, due to the tapered configuration of the worm bodies (and/or collars) the downstream areas will be of lesser cross-section, and thus, such feeding action by the worm flights will produce an essentially sustained high mechanical pressure upon the material, expressing liquids therefrom, and the liquids will flow through the openings between the screen bars to the exterior of the cage.

Where the material passes over collars 30, it is engaged by conventional breaker bars or lugs 50 which may be formed, for example, as extending pieces from a retainer plate or bar 52 secured to the cage by bolts 53 and serving also, in a preferred construction, to retain the stacked screen bars in aligned abutting relation as shown. The breaker lugs will resist rotation of the compacted material and thus tend to force the material generally axially of the press toward the discharge end thereof. Since the collars are mounted such that the shaft can rotate relatively freely with respect to the collars, there is no power required to rotate the collars against the friction of the compressed material being compacted against the collar surface. Thus, the action of the compressed material tending to retard any rotary movement of the collars (if there is any at all) is not transmitted as a resistive

force to the shaft, and it is therefore not necessary to supply power to the shaft for the purpose of overcoming such resistance to rotation.

Another feature of this construction is provided by the stationary mounting of the discharge collar 35, wherein the supporting bracket 36 prevents rotation therewithin. Since the areas of minimum cross-section are generally about this discharge collar, and at the discharge orifice defined by this collar and the stationary discharge ring 39, the material is compacted under very high pressure and is present as an essentially solid plug. Reduction of power needed to overcome friction at this location is also achieved in the same manner as previously described. In fact, probably the most significant power reduction is made available through use of the non-rotating discharge collar.

Furthermore, in the event that the press should be shut down under full load, as by accident due to a cut-off of the power supply to the drive, or by necessity due to some 20 breakage, the cake surrounding the discharge collar 35 becomes so hard that a great amount of power, perhaps in excess of the capabilities of the drive, is required to start again. Therefore, in many press constructions it is necessary to open the cage and chip away this highly compacted cake before starting up again.

However, with the present invention it is possible to withdraw the discharge collar 35 by releasing the bolts 37 and withdrawing the bracket 36. This will greatly increase the area of the discharge orifice, and the press can 30 then easily be started, with the high pressure adjacent the discharge relieved, and run empty until the hard cake is forced out, whereupon the discharge collar can be returned to its operative position and the press rapidly put back into normal operation. If desired, instead of ordinary bolts 37, special quick releasing types may be provided, for example, embodying special heads of irregular shape or the like which will release the sleeve 35 when turned, thus providing for ready withdrawal of the discharge collar.

It is also possible to control the cross-sectional area between the collar 35 and the discharge ring 39, as previously mentioned. This may conveniently be accomplished by placing shims or the like of desired thickness in the area of the spacers 38, thus adjusting the final position of collar 35 with respect to ring 39 when the bolts 37 are tightened. Obviously, equivalent apparatus can be utilized for adjusting the collar 35 axially to vary the discharge opening.

With reference to FIGS. 5 and 7, it is also possible to 50 mount the collars independently of, but aligned over, the main drive shaft. For example, as shown in these figures, split collars 30a can be provided with an internal diameter somewhat greater than the diameter of shaft 20, such that there is provision for some clearance therebetween, as shown particularly in FIG. 7. Each half of these collars can then be suitably affixed, as by welding, to breaker lugs 50a which will provide a convenient support for the collars maintaining them stationary and in proper position within the press, while the shaft 20 can rotate freely therewithin. If it is not desired to use the breaker lugs for such mounting purposes, other equivalent structure extending from the cage can conveniently be provided in accordance with the invention.

FIGS. 6 and 8 show a modified form of discharge collar which may be used where additional drainage is desirable at the final high pressure area just before the discharge orifice. In the particular embodiment shown the tapered discharge collar is not normally adjustable, and cooperates with a non-tapered stationary discharge ring 60. The last worm body 32b is threaded to the end of shaft 20, as shown in FIG. 6 and serves the further function of holding the previous worm bodies and collars axially in place upon the shaft. The end 62 of the shaft is of reduced diameter, and is received within and provides support for a sleeve bearing 65.

This bearing is in turn received in the end of the discharge collar body 68, which body is hollow and preferably is provided with a closure cap or cover 69. A section of the surface of body 68 is undercut for supporting screen bars, as indicated generally at 70 in FIG. 8. Inwardly of this section the hollow collar body is provided with radial openings 72 of substantial length, traversed by solid sections or pieces 73. A plurality of short screen bars 75 are placed about the collar body 68 within the section 70, and these screen bars are separated by conventional spacers as shown generally at 76. These bars are held in place by a wedge bar 78 at each side which is bolted into one of the solid segments 73. The collar body 68 is in turn threaded to an elongated hollow sleeve member 80, and thus there is an internal passage for expressed liquids conveying such liquids to the exterior, beyond the end bracket or plate 82. This bracket is in turn secured to the supporting bracket 36a (of essentially the same construction as previously shown) by bolts 37a.

This construction provides for extra drainage opening in the area of the final discharge collar, where the peak pressures are exerted upon the material, and thus a press so constructed is capable of draining away more liquid without any increase in complexity or size.

It is also possible to direct washing liquids into such a discharge collar to provide for a circulation of liquid within the discharge collar 68-80, as by conducting a flow of liquid thereinto, for the purpose of washing fine pieces of fibrous material or frosts which may tend to pass through the openings 76 in some circumstances and thus tend to block such drainage through the discharge sleeve unless washed away.

This washing liquid may be provided from any convenient source (not shown) either as fresh liquid such as water, or as liquid previously expressed in the cage, connected into a pipe 35 which extends interiorly of the discharge collar 68 and its mounting sleeve 80, and which is provided with a number of small spray openings in its end which will direct a spray of the supplied liquid against the exposed inside surfaces of the bars 75. Of course, if desired similar arrangements may be built into the body of the discharge collar 68 per se, however the use of a removable pipe and spray head as shown provides a convenient apparatus for this purpose which may be readily withdrawn if not needed, or for maintenance.

On some occasions when the press has been stopped and is subsequently started it is possible that a hard plug of compressed material may form adjacent the discharge end, particularly around the discharge collar. Rather than stopping the press to free such an initially formed plug, for example in the manner previously described, it may be possible to heat the structure of the press in the regions of such plug to such a high temperature that the plug of material will be burned and freed. Of course, the type of material being processed in the expressing press will to some extent determine the advisability of such procedure. In instances where such initial burning away of a tight plug is possible, heat for this source may be conveniently provided, in combination with the discharge sleeve constructions shown either in FIG. 2 or 6, by introducing live steam from a suitable source thereof through a pipe 100 and directing such steam through a spray head or the like against the interior surfaces of the collar. The steam will then heat the collar to a temperature high enough to burn away portions of the plug formed against the collar, and the plug will be freed. Instead of supplying steam it is also possible to supply a combustible mixture through the pipe 100 and to ignite such mixture at the end of such pipe interiorly of the discharge collar, directing the resultant flame and heat against the collar for the same heating purpose.

As noted, the provision of collars within which the shaft can rotate is significantly helpful in reducing friction of the compressed material against the collars within the press chamber, and this in turn results in a significant

decrease in heat due to friction. A press constructed in accordance with the invention can, therefore, operate satisfactorily with materials which heretofore presented problems due to ill effects thereon from such heating. Furthermore, it is possible to provide passages 110 within the shaft 20, together with conventional rotary seals in the area of the end 62 of the shaft, by means of which cooling liquid can be circulated through the shaft 20 for cooling thereof, and suitable passages can also be provided in the discharge sleeve (as through sleeve 35) for further cooling in the area if desired.

A further modified construction in accordance with this invention is shown in FIG. 9. Basically, this construction is of the same type as shown in FIGS. 6 and 8, but the stationary discharge collar, and the screen bars thereof, are tapered inwardly toward the discharge end of the press instead of outwardly. Thus, similar parts have been given the same reference numeral with the suffix *a*. This construction will provide for a relaxation of the mechanical pressure exerted upon the material passing over the stationary discharge collar, and the material therefore will expand somewhat in this region. If it is desired, liquids such as washing water or other liquid, or cooking liquor, may be added at this point by supplying such liquids to the interior of the discharge collar through the pipe 120. Since the material between the walls of the cage body and the discharge collar is undergoing a stage of relaxing mechanical pressure, it will tend to soak up materials thus added and flowing radially outward through the screen bars 75a.

FIGS. 10 and 11 show a further modification constructed in accordance with the invention. It should be noted that FIG. 10 is a sectional view taken on line 10-10 of FIG. 11, and that the upper portion of FIG. 10, although it appears in vertical section, is actually a horizontal section rotated 90° to simplify illustration of the construction. In this construction the main cage body shown as portions of frame 100, contains the main cage defining parts including breaker bars 102 and a ring 103 at the discharge end of the cage body mounted within frame parts 100. The rotating main shaft is not specifically illustrated in FIG. 10, but it will be understood that the pressure worms 105 are suitably affixed to such shaft for rotation therewith in a direction to force material toward the cage discharge, and the collar 107 is suitably mounted about the shaft, in alignment with the breaker bars 108. This collar may be free to rotate with respect to the shaft, in the same manner as previously described, if so desired.

On the opposite side of frame 100 there is a mounting plate 110 which is suitably secured to the frame in any suitable manner, and a pair of supporting bracket arms 112 (FIG. 11) extend rearwardly from the plate 110 and are affixed thereto, as by welding. A cross-bracket plate 114 is fastened to members 112 by bolts 115, and this cross plate provides a fixed mounting for a discharge collar support tube 118 which is fastened to the cross plate 114 by welding to a mounting ring 119. The tube 118 provides a mounting for the discharge collar which is shown by the general reference numeral 120, and which includes a collar body 122 threaded onto the tube 118 and supported coaxially of the main shaft.

The forward end of the collar body 122 carries a cover and clamp plate 123 which serves also to retain in position a number of screen bars 125 mounted side by side about the body 122. These bars are spaced slightly from each other by the usual spacers, such as previously mentioned in connection with FIG. 4, and expressed liquids thus can pass between the screen bars and through the openings 127 in the body 122, to flow outwardly through the tube 118 to a collection point.

Surrounding the discharge collar 120 is an axially adjustable discharge cone construction which includes a cone body 130 having a forward part fitted within the

ring 103, and slidably therein. The rearward portion of this body is substantially enlarged, as shown, and is provided with openings 132 which are traversed by screen bars 135. These screen bars are also spaced apart by the usual spacers, and are held in place by a clamping plate 137, thus providing drainage in an outward direction for expressed liquids. Such liquids can be collected in a trough 138 which is suitably mounted below the cone structure, and the cake material from which the liquid has been expressed will be discharged through the opening 140 between the collar body 122 and the cone structure. A baffle 142 is provided on the cone structure to direct the discharged cake over the trough 138.

The size of opening 140 can be regulated by adjusting the cone body 130 axially with respect to the discharge collar. This adjustment is provided by a pair of hydraulic rams, one of which is shown in elevation in FIG. 10, including a cylinder body 145 and an extending piston rod 147 which is suitably secured to the rear-most section 148 of the discharge cone body. The ram cylinder is mounted in a bracket 150 which is suitably bolted to the supporting bracket plate 112, as shown in FIG. 10. As will be seen from FIG. 11, this ram structure is duplicated on the opposite side of the discharge cone, and each ram may include conventional provisions (not shown) for clamping the piston rods thereof in a fixed position after appropriate adjustment has been made.

Power for the rams is provided by a pump 155 including an operating handle 156, and having a discharge line 158 which is connected in conventional manner to each of the hydraulic rams to direct hydraulic fluid under pressure thereto. This arrangement provides a convenient means, through manipulation of pump 155, to adjust the size of discharge opening 140, and to maintain such opening at a desired setting. The discharge cone construction, with its incorporated screen bars, cooperates with the stationary discharge collar 120 to provide a maximum of drainage area adjacent the discharge of the press, where the highest mechanical pressures are usually exerted upon the material from which liquid is being expressed.

While the adjustable cone construction is described and illustrated (FIGS. 10 and 11) in combination with a stationary discharge collar, it should be understood that this cone construction, with additional drainage provisions in particular, can also be used with a discharge collar which is carried by, and rotates with, the main shaft, as is conventional in many screw press constructions. In such instance, the adjustable cone will cooperate with the rotating collar to form a discharge orifice or opening of variable size.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. In an expressing press having a cage body including drainage openings in the walls thereof, a main drive shaft extending through said cage body, a plurality of pressure worms including supporting bodies mounted in spaced apart relation upon said shaft and worm flights extending into close proximity with the walls of said cage, means providing a driving connection between said shaft and said worms for concurrent rotation thereof, collars mounted upon said shaft between adjacent said pressure worms, bearings between any of said collars and said shaft providing for independent rotation of each collar on said shaft, spacer members on said shaft located interiorly of said bearings maintaining the positioning of said worm bodies axially of said shaft, stationary breaker lugs extending adjacent to said collars to resist rotation of material forced over said collars under pressure from the preceding worm flight, at least some of said pressure worm bodies

and/or collars being tapered to increase in thickness toward the discharge end of said cage body to decrease the area through which the material is passed, and drive means connected to rotate said shaft causing said worm flights to force material through such areas of decreasing cross-section exerting an expressing force on the material.

5 2. In an expressing press having a cage body including drainage openings in the walls thereof and having inlet and discharge openings at opposite ends thereof, said 10 body being of uniform cross sectional dimension between its said inlet and discharge openings, a discharge ring mounted at one end of said cage and defining said discharge opening, a main drive shaft extending through said cage body, a plurality of pressure worm bodies mounted in spaced apart relation upon said shaft and having worm flights extending to adjacent the walls of said cage body, means providing a driving connection between said shaft and said worms for concurrent rotation thereof in a direction to force material toward said 15 discharge openings, collars mounted upon said shaft between adjacent said pressure worms, breaker lugs extending from said cage body adjacent to said collars to resist rotation of material passing over said collars under pressure from the preceding worm, means connected to rotate 20 said shaft causing said worms to force material through said body and over said collars thus exerting an expressing force on the material, a discharge collar having a major portion of its length located inside said cage body and being coaxial with said shaft, a portion of said discharge 25 collar extending into said discharge ring and forming therewith the said discharge opening, at least one of said discharge ring and said discharge collar having a surface tapered toward the other end cooperating to define the passage through which the pressed material is 30 expelled, and means mounting said discharge collar in normally stationary position from said cage body providing for rotation of said shaft with respect to said discharge collar to reduce the power input necessary to rotate said shaft and to reduce heating of the material forced past 35 said discharge collar.

3. In a continuous screw press of the type defined in claim 2, the combination wherein said stationary discharge collar is a hollow body, and means defining drainage openings in said discharge collar for further drainage of liquids and the like from the material subjected to the higher pressures exerted on the material surrounding said discharge collar near the discharge opening of said press.

4. In a continuous screw press as defined in claim 3, the combination including a means for directing a flow of washing liquid against portions of said drainage opening defining means interiorly of said discharge collar to flush the interior thereof of collections of foots, sediment, and the like.

5. In a continuous screw press as defined in claim 2, means for cooling said stationary discharge collar from the discharge end of said screw press, and means for cooling said rotating shaft from the opposite end of said shaft from said discharge collar.

6. In a continuous screw press of the character described the combination of a cage body having a discharge opening, means for exerting pressure on material within said body and simultaneously conveying the material through said body and said discharge opening including a rotatable shaft and at least one pressure worm affixed thereto, drive means for rotating said shaft, means cooperating with said worm and said cage body to resist the passage of material through said body providing for an increase of mechanical pressure upon the material as it is conveyed through said body, a stationary discharge collar mounted coaxially with said shaft adjacent said discharge opening and cooperating therewith to define a discharge orifice, said discharge collar being tapered to a smaller diameter at the end thereof closest to said discharge opening providing for a releasing of the mechanical pressure exerted upon material passing about said

discharge collar to said discharge opening, means defining drainage openings in the walls of said cage body for passage of liquids expressed from the material to the exterior of said cage body, means defining openings in said discharge collar of sufficiently small size to prevent the passage of substantial amounts of the material into said openings, and means supplying a flow of washing liquid to said openings in said discharge collar for mixture with the material passing over said discharge collar.

7. In a continuous screw press as defined in claim 6, means for supplying steam through said openings in said discharge collar for mixture with the material passing over said discharge collar.

8. In a continuous screw press of the character described the combination of a cylindrical cage body having inlet and discharge openings at opposite ends thereof and having drainage openings in the walls of said cage for passage of expressed liquids and the like, said cage body being constructed to retain therein material subjected to mechanical pressures of the order of 5000 to 6000 p.s.i., a rotatable shaft extending coaxially within said cage body, at least one pressure worm driven by said shaft and rotating within said body with minimum clearance between said worm and the inner walls of said body, means for obstructing rotation of the material within said cage body downstream of said worm toward said discharge opening to present an obstruction to flow of the material and causing the creation of high mechanical pressures upon the material to express liquids and the like therefrom, a discharge collar within said cage body coaxially arranged with respect to said shaft, means mounting said discharge collar from said cage body maintaining said discharge collar normally stationary to present a stationary surface about which the compressed material must pass prior to exit thereof from the cage body through said discharge opening, a circular discharge ring surrounding said discharge collar adjacent the end of said discharge collar farthest down stream of said worm and engaged with said cage body at said discharge opening to form with said discharge collar an orifice at said discharge opening through which material is discharged, said ring having a plurality of spaced screen bars mounted in slightly spaced relation therein to form discharge openings in said ring through which expressed liquids may pass, at least one of said discharge collars and said discharge ring having a portion tapering toward the other to provide a discharge opening which is of less effective cross sectional area than the cross sectional area defined by the parts of said discharge collar within said cage and the walls of said cage surrounding said discharge collar, and means included in the mounting of said ring providing for adjustment of the position of said ring with respect to said discharge collar for changing the size of said orifice.

9. Apparatus as defined in claim 8 wherein a plurality of screen bars are mounted in said discharge collar in slightly spaced relation to each other forming drainage openings into the interior of said discharge collar, and means for conducting from said discharge collar liquids and the like expressed through such drainage openings into the interior of said discharge collar.

10. In an expressing press as defined in claim 2, means forming a mounting for said collars mounted upon said shaft including bearing means providing for free rotation

of said collars upon said shaft between adjacent said pressure worms.

- 5 11. In a continuous screw press having a cage body, a main drive shaft extending through said cage body, a plurality of pressure worms mounted in spaced apart relation on said shaft, means providing a driving connection between said shaft and said worms for concurrent rotation thereof, stationary breaker lugs extending from said cage body toward said shaft at locations between said worms to resist rotation of material passing from the preceding worm, collars mounted on said shaft for free rotation thereon and extending into closely spaced relation with the adjacent breaker lugs providing for free movement of the collars with respect to said lugs, and drive means for rotating said shaft causing said worms to force material through said body and over said collars without driving said collars in rotation.
- 10 12. In a continuous screw press of the character described the combination of a cage body having a discharge opening defined by a circular discharge ring, said cage body being constructed to hold therein material under mechanical pressures of as much as 10,000 p.s.i., means for exerting high mechanical pressure upon material within said body and simultaneously conveying the material through said body and said discharge opening, said means including a rotatable shaft and at least one pressure worm affixed thereto, drive means for rotating said shaft, means defining drainage openings in the walls of said cage body for passage of liquids expressed from 15 the material to the exterior of said body, a stationary discharge collar inside said cage body coaxial with said shaft extending into said ring to define therebetween a discharge orifice, means mounting said discharge collar from said cage body maintaining said discharge collar normally stationary with respect to said rotatable shaft thereby reducing the power required to rotate said shaft and reducing frictional heat created in the material being forced between said discharge collar and the walls of said cage body and thence through said ring, and means 20 for heating said discharge collar to temperatures in the region of the combustion temperature of material being processed through said press to burn away hard plugs of pressed material from about said discharge collar to free such plugs and provide for subsequent continuous operation of said press and passage of the material being processed therethrough.
- 25 13. In a continuous screw press as defined in claim 2, bearing means carried by said stationary discharge collar and engaging said drive shaft to support said shaft adjacent said discharge ring.
